CAN OR SIMILAR ARTICLE

Carmen T. Mascia, Westmont, Ill., assignor to Continental Can Company, Inc., New York, N.Y.

Continuation-in-part of abandoned design application Ser.
No. 133,461, Apr. 12, 1971. This application Apr. 20,
1972, Ser. No. 246,102

Term of patent 14 years

Int. Cl. D9—03

U.S. Cl. D9—216

FIG. 1 is an elevational view of a can or similar article embodying my new design;

FIG. 2 is an elevational view looking from the rear of FIG. 1;

FIG. 3 is a top plan view; and

FIG. 4 is a bottom plan view.

This application is continuation-in-part of application Ser. No. D. 133,461, filed Apr. 12, 1971, now abandoned.

I claim:

The ornamental design for a can or similar article, as shown and described.
